UNITED STATES PATENT OFFICE.

WILLIAM O'SHEA, OF LINCOLN, NEBRASKA.

PERFORATED PAPER TABLET.

SPECIFICATION forming part of Letters Patent No. 294,803, dated March 11, 1884.

Application filed March 3, 1883. (Model.)

To all whom it may concern:

Be it known that I, WILLIAM O'SHEA, a citizen of the United States, residing at Lincoln, in the county of Lancaster and State of 5 Nebraska, have invented certain new and useful Improvements in Perforated Paper Tablets; and I do hereby declare that the following is a full, clear, and exact description of the same, reference being had to the annexed 10 drawings, making part of this specification, and to the letters and figures of reference marked thereon.

This invention relates to certain new and useful improvements in perforated paper tablets, and has for its object to provide such a 15 device whereby several distinct and separate tablets or blocks of different sizes may be embraced in one article, so as to enable the user to take only the amount necessary for his use 20 at one time without the trouble or cost of keeping on hand a variety of different-sized tablets, as is usually the case with accounts and others.

The invention therefore consists in providing 25 the several sheets of paper composing a tablet with lines of perforations arranged in such a manner as to divide the same into several distinct parts of different sizes, as will be hereinafter described with reference to the 30 accompanying drawing.

In the drawing, which represents a perspective view of a tablet or block constructed according to my invention, the several sheets of 35 paper composing said tablet being perforated vertically and horizontally, so as to divide

said sheets into several distinct parts, A B C D E F, each of these several parts being of a size larger or smaller than the others, to suit the user's convenience, and when the sheets are put together to form a single tablet or 40 block the lines of perforations divide the same into minor tablets or blocks of various sizes, thus doing away with the usual necessary practice of keeping on hand a variously-sized lot of such articles. Should only a small 45 piece of paper be required for use, the same can be detached from the sub tablet or block E, leaving the balance of the sheet intact, and should it be desirable to use both sides of the paper, this detached portion of the sheet may 50 be folded over, as at E E, upon an adjoining section, this operation being similarly performed with any of the several sections, as convenience may require; also, by a tablet or block constructed according to my invention, 55 memorandums may be kept upon a portion of the same without detachment, while the other portions may be used and torn off at pleasure.

Having now fully described my invention, what I claim as new, and desire to secure by 60 Letters Patent, is—

As an improved article of manufacture, a tablet divided into blocks or sheets of different sizes by lines of perforations, substantially as and for the purpose set forth.

WM. O'SHEA.
